PRESSURE DRILLING HEAD

Albert Pranger and Samuel Allen Guiberson, III,
Dallas, Tex., assignors to The Guiberson Corporation,
Dallas, Tex., a corporation of Delaware

Application January 18, 1938, Serial No. 185,482

15 Claims. (Cl. 255—1)

This invention relates to an improved pressure drilling head.

In the oil well industry, many advantages result from drilling in under pressure, but many difficulties and obstacles result from drilling in under pressure. A square kelly is frequently employed, which is rotated by the rotary table, while the drill pipe is round, and outside collars are frequently employed. Under these conditions, it has proved to be very difficult to drill without considerable loss of pressure. An important object of this invention is to cure these difficulties by providing a packer of unique construction which will accommodate a kelly of any outside configuration, and which will permit the passage of the outside collars, and will also automatically accommodate or conform to the shape of a round drill pipe. By this arrangement, the pressure drilling head provides a pressure seal, when a flat-sided kelly or drill stem is employed, so that there is very little loss of pressure, and as the collars or round drill pipe is passed through the drilling head, the packer will conform to the configuration of the same, so as to hold the pressure.

We have shown a specific form of the invention by way of illustration, and not by way of limitation in the accompanying drawings.

Fig. 1 is a vertical view of the pressure drilling head, the square kelly, the drill pipe, and one collar, certain of the parts being shown in cross section.

Fig. 2 is a plan view, partly in cross section, taken on the line 2—2 of Fig. 1, looking downwardly.

Fig. 3 is a perspective view of the Kelly clamp, which is shown in the upper part of Fig. 1.

Fig. 4 is a cross sectional view on the line 4—4 of Fig. 1, showing a square kelly, packed off in the rubber sleeve or packing member.

Fig. 5 is a view similar to Fig. 4, but showing a round drill pipe packed off in the rubber sleeve or packing member, and.

Fig. 6 is a view partly in cross section, taken on the line 5—5 of Fig. 1, looking to the left.

The square kelly 1 is rotated by the rotary table, as is well understood in the industry. A Kelly clamp composed of two sections, 2 and 3, is placed around the kelly 1, and has an inside dimension and shape to conform to the outside of the square kelly. Two halves of the Kelly clamp are bolted together by the bolts 4 which pass through apertures 5 in ears 6, which form a part of each section of the Kelly clamp. Each of the sections of the Kelly clamp are provided

with downwardly extending skirts 7 which have straight inner faces, as is shown in Fig. 3, which inner faces lie against the opposite sides of the square kelly 1. It is, therefore, obvious that as the square kelly 1 is rotated, the Kelly clamp would be rotated with the same, but as the well was drilled deeper, the kelly would pass longitudinally downwardly through the Kelly clamp, and if it were desired to pull the kelly upwardly, the kelly would slide upwardly between the members of the Kelly clamp.

Each section of the Kelly clamp is provided with an outstanding collar 8, which normally rests against the upper surface of a gland 9, which is circular (except for the vertical channels 11) on its interior, as shown in Fig. 2, and which has an outstanding flange 10. The vertical channels 11 receive the straight sides of the skirts 7 of the Kelly clamp, as shown in Fig. 1. The outer periphery of the gland 9, below the flange 10, is circular, as shown in Fig. 2, except for diametrically opposite keyways 12. The rotary housing 13 is provided at its upper end with threads 14 on which is screwed a ring 15, which is provided with a keyway 16. The rotary housing 13 is provided with a similar keyway in alignment with the keyway 16, and a key 17 is positioned in the said keyways, and, if desired, it may be extended into the keyway 12, and is held in position by a bolt 18, which passes through the key 17 and the ring 15. From the above construction, it is apparent that when the square kelly 1 is rotated by the rotary table, not shown, the Kelly clamp is likewise rotated, which in turn, rotates the gland 9, and through the keyway 12 and key 17, and by means of the bolts 19 the ring 15 and the rotary housing 13 is likewise rotated. It will, of course, be understood that there are diametrically opposite keys 17, as is shown in Fig. 2, but if desired, a greater number of keys may be employed.

It is, of course, obvious that the kelly would rotate the packing member 41, which is under compression, and this would rotate the rotary housing independently of the Kelly clamp as well as independently of the keyway 12 or the key 17 or the ring 15. If the Kelly clamp is omitted entirely, the gland 9 would rotate with the rotary housing through the ring 15 and bolts 50 19 and this is especially true since there is nothing to retard the rotation of the gland 9. It is also obvious that, regardless of whether the clamps 2 and 3 are used or are not used, it is not essential that the keys 17 project into the key-

ways 12 for the gland 9 is locked to the ring 15 by means of the bolts 19.

The flange 10 is provided with apertures which receive bolts 18, there being four, shown in Fig. 2, but obviously, a greater or lesser number may be used, which bolts extend downwardly and screw into the rings 15, to cause the gland and the rotary housing to rotate as a unit and to serve as a means to compress the packing. The rotary housing 13 and the ring 15 cannot be moved upwardly, so that the net result is that the member 9 is moved downwardly when the bolts 19 are screwed down or tightened, and as a result, compresses the packing member which will be hereinafter described.

The rotary housing 13 is provided with a shoulder 20 which receives, above the same, an inner race member 21, thereby holding the said race against downward movement. The member 13 is also provided with a lower shoulder 22, which receives a lower inner race member 23. The upper and lower race members are, of course, circular on their outer faces and are provided with circumferential grooves, as is well known in the art, which receive rollers 24 and 25 respectively, which contact sloping surfaces 26 and 27 respectively of upper and lower outer race members 28 and 29 respectively.

An outer housing 30 is provided, which surrounds the rotary housing, except that it does not extend as far upwardly as the rotary housing, which outer housing is provided with threaded bolt holes 31, which receive bolts 32, which have heads which overlie a cover plate 33. The cover plate is provided with an oil duct 34, which is closed by a plug 35. Lubricating oil may be inserted through the said duct so as to oil the parts below the same, including the rollers. The outer housing 30 is held stationary by being rigidly attached to the casing of the well, not shown.

The cover plate 33 is provided with a downwardly extending lug 36 which, when the bolts 32 are tightened, presses the outer race member 28 downwardly so as to contact the upper rollers 24, which in turn tends to press the inner race member 21 downwardly, and as this member 21 overlies the shoulder 20, the entire rotary housing 13 would be moved downwardly so that the lower shoulder 22 would engage the lower inner race member 23, and press the lower rollers 25 into engagement with the lower outer race member 29. In order to adjust the bearings, therefore, it is only necessary to tighten or loosen the bolts 32.

If desired, adjusting shims 37 may be inserted between the cover plate 33 and the upper portion of the outer housing 30.

The rotary housing 13 is provided with a shoulder 38, and below the shoulder the rotary housing 13 continues downwardly forming a skirt 39 with a reduced diameter, as shown in Fig. 1. Immediately below the lower end of the gland 9 is a ring 40, and below the ring 40 and above the shoulder 38 is a packing member 41. The compression of the packing member 41 may be varied by tightening or loosening the bolts 19, thereby moving the gland 9 down or up, and compressing or relieving the compression of the packing member 41 through the ring 40.

As shown in Fig. 1, the packing member 41 is corrugated, by having internal circumferential channels 42 and external circumferential channels 43, with ridges 44 between the said channels or valleys. At the upper end of the packing

member 41, there is a flange 45 extending outwardly and in contact with the lower surface of the ring 40. Near the lower end of the packing member 41 is a flange 46, under which lies the shoulder 38. When the member 9 and ring 40 move downwardly, as above described, so as to compress the packing member, the ridges between the inner circumferential channels 42 are moved into packing engagement with the kelly, the drill pipe or the collar and the ridges between the outer circumferential channels 43 are moved into packing engagement with an inner rotary housing 13.

The packing member 41 is made of any resilient packing material, and the inner periphery is circular for both the round drill pipe, or the square kelly. Preferably, it is slightly smaller than the inner diameter of the round drill pipe, or the shortest distance between opposite sides of the square kelly. If a square kelly is to be inserted, in the packing member 41, the corrugated inner and outer surfaces thereof will permit a sufficient change of configuration, so as to conform to the square kelly, or if a drill pipe is to be passed through the same, it will, of course, conform to the contour of the outside of the drill pipe.

The usual collar 47 serves as a connecting means between the kelly and the drill pipe 48.

30 The collar is larger than the drill pipe, provided an external collar is employed, and the lower inner surface of the packing member 41 is provided with a flange 49, which forms an outwardly extending surface so that, as the collar 47 is raised, it will contact the beveled surface of the flange 49, so the packing member will not be distorted vertically to a material extent, as would be the case if the lower end of the packing member formed a horizontal plane.

40 The usual packing 50 is interposed between the lower portions of the stationary outer housing 30 and the rotatable inner housing 13, which packing prevents the oil that has been inserted through the oil duct 34 from draining into the well casing. From the above description, it is apparent that when the kelly 13 is rotated, everything in the drawing is likewise rotated, except the outer housing 13 and the parts directly secured thereto, including the outer race members 28 and 29, which parts are held stationary. It is also apparent, that owing to the unique construction of the packing member 41, a pressure drilling head is provided which will accommodate both a square and a round kelly, as well as a collar or drill pipe. It is further to be noted that, the pressure or packing engagement between the inner housing 13 and the packing member, as well as the packing pressure between the packing member, and the kelly, collar, or pipe in the same may be readily adjusted by suitably rotating the bolts 18.

55 In operation the rotary housing 13 simply rotates and has no longitudinal movement relative to the outer housing and the well casing. When running in the drill pipe, it is not necessary to have the packing or any of the members above the packing in place. However, before the kelly is attached to the drill pipe the packer 41 and the parts which press the packer downwardly are inserted and the kelly is then attached to the drill pipe. The kelly may then be lowered into the housing into the position shown in Fig. 1, at which time the bolts 18 should be tightened so as to compress the packer downwardly on the shoulder 38 and so as to cause the corrugated

5 packer to pack off the space between the kelly and the housing 13 regardless of whether the kelly is round or square. In pressure drilling the normal pressure used would be employed and the pack off should be sufficiently tight to withstand these normal pressures while the packer is resting on the shoulder 38. If now the operator drilled into a high pressure zone the high pressures would cause the packer to be pushed upwardly since the lower end thereof extends into the high pressures and this would cause the seal to be tightened so as to resist these pressures and as a matter of fact, the higher the pressures the tighter the seal. We, therefore, have a manually controlled means, namely the bolts 16 and parts associated therewith to compress the packer to withstand normal pressure and we have an automatic means, namely, the excess pressures in the well to cause the seal to be tightened while moving the lower end of the packer upwardly when the abnormal pressures are experienced. Regardless of whether we have the normal pressure or the abnormal, the packer is sufficiently resilient to take care of the passage of the collars so that after boring 10 into the high pressure zone the entire drill pipe may be removed by simply pulling it upward. Of course, you would not wish to entirely remove the drill pipe if the high pressures were being experienced, but the drill pipe can be pulled up to a point above any member which might seal the well, such as the usual gate valve. If a gate valve were employed, obviously, you would close the gate valve after the bit had been raised above it and while the lower portion of the drill pipe was still within the packer, therefore preventing a blow out. It is the usual custom in order to remove the bit to first remove the pressure head, and of course, after the gate valve would close 15 this could be done as is the accepted practice.

20 We realize that many changes may be made in the specific form of the invention which is shown by way of illustration and not by way of limitation in the accompanying drawings, and we therefore reserve the right to make all changes in the specific form thereof, except as we may limit ourselves in the appended claims.

25 Having now described our invention, we claim:

1. In a drilling head for an oil well, a resilient packing member provided with circumferential inner and outer valleys, with intervening ridges and adapted to receive either a square member or a round member, and manually controlled means to control the compression of said packing means and a rotatable housing in which said packing member is mounted.

2. In a drilling head for an oil well, a rotatable housing, a resilient packing member corrugated in vertical cross section forming inner and outer valleys and ridges and having a bore extending therethrough, adapted to receive and pack off a flat or round-faced drill member, and manually controlled means to regulate the compression of said packing member, the lower end of said member being exposed to the gas pressures in the well.

3. In combination, a rotatable housing, a resilient packing member corrugated in vertical cross section forming inner and outer valleys and ridges and having a bore extending therethrough adapted to receive either a flat or round-faced drill member, contacting shoulders on said housing and packing member to hold the lower end of said packing member against downward

5 movement, and means to press downwardly on the upper end of the said packing member to cause said packing member to make a pressure seal between said rotatable housing and said drill member.

4. In combination, a rotatable housing, a resilient packing member corrugated in vertical cross section forming inner and outer valleys and ridges and having a bore extending therethrough adapted to receive either a flat or round faced drill member, contacting shoulders on said housing and packing member to hold the lower end of said packing member against downward movement, and means to regulate the pressure exerted by said packing member in sealing the space between the rotatable housing and the drill member.

5. A well drilling apparatus including a rotatable housing through which a flat sided drill stem, a round drill pipe or an outside collar may be passed, a packing within and rotatable with said housing, said packing having circumferential corrugations, and being sufficiently resilient to permit vertical passage of the flat-sided drill stem, drill pipe or collars, while rotating and adapted to hold the well pressure and a gland to regulate the compression of said packing.

6. A well drilling apparatus including a rotatable housing through which a flat sided drill stem, a round drill pipe or outside collar may be passed, a packing within and rotatable with said housing, said packing having circumferential corrugations, and being sufficiently resilient to permit vertical passage of the flat-sided drill stem, drill pipe or collars, while rotating and adapted to hold the well pressure and a gland to regulate the compression of said packing, a stationary housing in which said rotatable housing is mounted, and anti-friction bearings between said stationary and rotatable housings.

7. A well drilling apparatus including a rotatable housing through which a flat sided drill stem, a round drill pipe or outside collar may be passed, a packing within and rotatable with said housing, said packing having circumferential inner and outer corrugations, and being sufficiently resilient to permit vertical passage of the flat-sided drill stem, drill pipe or collars, while rotating and adapted to hold the well pressure, a gland to regulate the compression of said packing, a stationary housing in which said rotatable housing is mounted, and anti-friction bearings between said stationary and rotatable housings, and means whereby said bearings may be simultaneously adjusted.

8. In combination, a flat-sided kelly, a Kelly clamp rotatable therewith, a member provided with a keyway rotatable with said Kelly clamp, a housing carrying a key projecting into said keyway whereby said housing rotates with said member, a packer in said housing and provided with a circular bore, but being sufficiently resilient to receive a flat-sided drill member and being adapted to prevent the loss of gas pressure, said first named member being adjustable relative to said packer to govern the amount of pressure of said packer.

9. In a combined pressure drilling head and oil saver adapted to seal the upper end of an oil well, a rotary housing, means to prevent the longitudinal movement of said housing, a circumferentially corrugated packer forming inner and outer valleys and ridges and positioned within the housing and having a bore extending

therethrough to receive a drill member, said packer being sufficiently resilient to allow the passage therethrough of either flat sided or round drill members while sealing the space between the rotary housing and the drill member, contacting stops on said packer and housing to limit the downward movement of said packer, means to force said packer downwardly to cause said packer to seal the space between the housing and the drill member, the lower end of said packer being exposed to the pressures within the oil well so that if high pressures should be encountered the packer would be forced upwardly from its stop and form a tighter seal between the housing and drill member than before the high pressures were encountered.

10. In a combined pressure drilling head and oil saver adapted to seal the upper end of an oil well, a rotary housing, means to prevent longitudinal movement of said housing, a circumferentially corrugated packer provided with a bore adapted to receive either a round or a flat sided drill member or the outside collars thereon and to seal the space between the housing and drill member, adjustable means to compress the packer downwardly so as to pack off the space between the housing and drill member when normal pressures are encountered, the lower end of said packer being exposed to the pressures in the well so that if abnormal pressures are encountered, the lower portion of the packer will be moved upwardly to hold said abnormal pressures, the inner dimensions of said rotary housing and adjusting means being larger than the drill member or the collars thereon so that the drill member and collars may be passed upwardly and downwardly through the head while the head and packer are intact.

11. A combination pressure drilling head and oil saver including a rotatable housing, a packing member having a bore therethrough and seated in said housing, said packing member having circumferentially extending ridges and grooves and being sufficiently resilient to accommodate either a flat sided or a round drill member and a gland operable on the upper surface of said packing member to compress said packing member so as to seal the space between said drill member and said housing.

12. A combination pressure drilling head and oil saver including a rotatable housing, a packing member having a bore therethrough and seated in said housing, said packing member having circumferentially extending ridges and

5 grooves and being sufficiently resilient to allow the vertical passage therethrough of a flat sided or round kelly or a drill pipe or a drill pipe collar while holding the well pressure and manually controlled means operable on the upper part of said packing member to adjust the pressure exerted by said packing member on said housing and the member within the bore of the packing member.

13. A combination pressure drilling head and oil saver including a rotatable housing, a packer therein provided with a bore of such size as to permit vertical passage of a flat sided drill member a round drill pipe or the outside collars on said drill pipe while rotating and without loss of well pressure, said packing member having yieldable corrugations forming inner and outer valleys with intervening ridges for engaging the drill pipe and collars without loss of well pressure and a gland rotatable with the housing and adapted to force the upper end of said packer downwardly so as to compress said packer.

14. A combination pressure drilling head and oil saver including a rotatable housing, a packing member having a bore extending vertically therethrough and being of such a configuration and the packing being of such resilience as to allow the vertical passage therethrough of a flat sided drill member or a round drill member or an outside collar and manual means to adjust the compression of said packing member, the inner dimensions of said housing and manual means being larger than the said collars so that the collars can be pulled through the head without loss of well pressure.

15. A combination pressure drilling head and oil saver including a rotary housing provided with a seat, a packing member provided with circumferentially extending corrugations, said packing member resting on said seat, a gland to adjust the compression of said packing member, said packing member being provided with a bore adapted to admit the vertical passage therethrough of a flat sided or a round kelly or a drill pipe or an outside coupling without loss of well pressure when drilling, said packing member permitting the vertical removal of the flat or round kellys, the drill pipe and the outside collars without loss of well pressure when it is desired to remove the drilling equipment from the well.
